175,686

BUILDING

Ernest R. Konikson, Erskine, Minn.

Application August 16, 1954, Serial No. 31,873

Term of patent 7 years

(Cl. D13—1)

Fig. 1.

Fig. 2.

Fig. 3.

Fig. 4.

I claim:

The ornamental design for a building, as shown.
